PROPELLER

Frank Leffel, Baltimore, Md.

Application February 25, 1941, Serial No. 380,435

2 Claims. (Cl. 115—32)

This invention relates to improvements in propellers for boats and vessels and has for its object to provide a device that can be readily attached to a boat, or vessel, of any construction for propelling same, and which can be readily removed therefrom when desired.

The invention consists of the novel construction and arrangement of the parts and combination of parts hereinafter more fully set forth in the following specification and pointed out in detail in the appended claims.

In the accompanying drawings:

Figure 1 is a side elevation of my invention secured to the stern of a boat, the driving arm being in the extended position.

Figure 2 is a similar view to Figure 1 with the driving arm in contracted position.

Figure 3 is a top plan view of Figure 1.

Figure 4 is a section on the line 4—4 of Figure 3.

Figure 5 is an enlarged detail view of one of the frames in which propeller blades are mounted.

Referring to the accompanying drawings, forming part of this specification, and in which like reference numerals designate like parts throughout the several views thereof, I designates the stern of a boat to which my invention is applied, and 2 is a frame that is secured to and projects beyond the stern of the boat. The said frame 2 is provided with a seat 3 for the operator. Hinged to the front of the frame 2 at 4, is a piece 5 which rests on the bottom of the boat and has a cross-piece 6 pivoted thereto at 7 on which the feet of the operator rests. Wires or ropes 8 are secured to the outer ends of the cross-piece 6 and extended back and are connected to the outer ends of the cross-piece 9 which latter is pivoted at 10 and has a rudder 11 projecting downwardly from each end thereof. The operator can guide the boat by turning the cross bar 6 back and forth with his feet, which in turn rocks the cross-bar 9 and turns the rudders 11. The propellers are operated through the medium of the wheel 12 which is pivoted on top of the standard 13 mounted on top of the frame 2. Cords or wires 14 are secured to the outer ends of the wheel 12 and extend back between the pins 15 and over the pulleys 16 and down through the propeller frame 17, one of said cords passing over the pulley 18 mounted on a rod 19 in the lower end of the propeller frame 17, and the ends of both of the cords or wires 14 being secured to the cross bar 20, which latter has its ends projecting through the slots 21 in the side

5 of the propeller frame 17 and is adapted to move up and down in said slots. A collapsible arm 22 is pivoted to the rod 19 and has one of its joints pivoted to the sliding rod 20. On one end of the collapsible arm 22 is a frame 23 and on the other end a frame 24, each having slots 25 in which the ends of the arm 22 operate. The frame 23 has propeller blades 26 pivoted at 27 which normally rest against the cross rods 28 which latter hold the blades 26 in position when pushing against the water, and the frame 24 has propeller blades 29 pivoted at 30 which normally rest against the cross-rods 31 which latter hold the blades 29 in position when pushing against the water. By turning the wheel 12 back and forth the rod 20 will be drawn up and down in the slot 21, through the medium of the cords, or wires, 14 causing the collapsible arm 22 to be extended, as shown in Figure 1 of the drawings, or collapsed as shown in Figure 2 of the drawings. When the collapsible arm 22 is forced out to the extended position the propeller blades 26 are in their normal or closed position and act against the water to push the boat forward, and when the arm 22 is collapsed the propeller blades 26 tilt on their pivots and the propeller blades 29 close and act against the water to push the boat forward, thus the propeller blades 26 act against the water when the arm is extended and the propeller blades 29 act against the water when the arm 22 is collapsed. The frame 17 is secured to the sprocket wheel 32 and is adapted to turn therewith. The said sprocket-wheel 32 is reciprocally mounted in the frame 2 and a sprocket chain 33 connects said sprocket wheel 32 with a small sprocket-wheel 34 mounted on the front of the frame 2. A pin 35 projects from the side of the frame 2 and is adapted to project into one of the links of chain 33 to hold the propeller frame 17 securely in position. When it is desired to drive the boat 1 backward, the chain 33 is pulled away from the pin 35 and by pulling on the chain 33 the sprocket wheel 32 is revolved until it makes a one-half turn which turns the propeller frame 17 around in the opposite position. The action heretofore described to extend and collapse the arm 22 for driving the boat forward is the same for driving it backward after the propeller frame 17 has been turned.

50 Having thus described my invention, what I claim is:

1. A propeller for boats, vessels, and the like, comprising a frame adapted to be secured to the stern of a boat, a seat secured to said frame, a cross piece pivoted to said frame in front of said

seat, a cross pivoted to said frame back of said seat, a rudder secured to each end of the cross piece back of said seat and extending below said frame, means connecting the ends of the said two cross pieces for controlling the movement of the rudders, a collapsible arm secured to said frame, means for collapsing and extending said arm, and propeller blades pivotally mounted on opposite ends of said arm, the blades on one end of said arm adapted to operate against the water when said arm is extended and the propeller blades on the opposite end of said arm adapted to operate against the water when said arm is collapsed.

2. A propeller for boats, vessels and the like, comprising a frame adapted to be secured to the stern of a boat, a cross piece pivoted to said

frame, a rudder projecting downwardly from each end of said cross piece, means connected to said cross piece to control the movement of said rudders, a propeller frame reciprocally mounted in, and extending below, said first named frame, means for reciprocating said propeller frame, a collapsible arm secured to said propeller frame, means for collapsing and extending said arm, and propeller blades pivotally mounted on opposite ends of said arm, the blades on one end of said arm adapted to operate against the water when said arm is extended and the propeller blades on the opposite end of said arm adapted to operate against the water when the said arm is collapsed.

FRANK LEFFEL.
